UNITED STATES PATENT OFFICE.

EUGENE IRVING HANSON, OF NEW ROCHELLE, NEW YORK, ASSIGNOR TO H. R. MALLINSON & CO., OF NEW YORK, N. Y., A FIRM COMPOSED OF HIRAM ROYAL MALLINSON AND E. IRVING HANSON.

DESIGN FOR A TEXTILE FABRIC.

50,305.

Specification for Design.

Patented Feb. 13, 1917.

Application filed September 23, 1916. Serial No. 121,887. Term of patent 3½ years.

To all whom it may concern:

Be it known that I, EUGENE IRVING HANSON, a citizen of the United States of America, and a resident of New Rochelle, in the county of Westchester, State of New York, have invented a new, original, and ornamental Design for a Textile Fabric, of which the following is a specification, reference being had to the accompanying drawing, showing my design.

The drawing shows a face view of a portion of fabric bearing my design.

Copies of this patent may be obtained for five cents each, by addressing the "Commissioner of Patents, Washington, D. C."

In the drawing *a* designates a spiral produced upon a disk-like field *b*, having a curved stripe *c* in close proximity to a portion of the periphery of said disk-like field, the whole being produced upon the background *d*.

The design is intended to be repeated on the fabric.

I claim:—

The design for a textile fabric as shown and described.

E. IRVING HANSON.
